RECORD CARD READER

Edward Lincoln Brown, Carmel, N.Y., Rudolph Henry Koepf, Orange, Conn., and Howard Strudwick Noel, Cupertino, and Donald Harry Wood, Santa Clara, Calif., assignors to International Business Machines Corporation, Armonk, N.Y., a corporation of New York

Filed Aug. 1, 1966, Ser. No. 3,275

Term of patent 14 years

(Cl. D26—5)

FIGURE 1, being a front perspective view of a record card reader, showing our new design; and

FIGURE 2 is a rear elevational view thereof.

The essential features of our design reside in the portions shown in full lines, it being understood that the broken lines representation of a record card tray and a support in FIGURE 1 is for purposes of illustration only.

For example, a card tray and support are shown encircling the record card reader. In addition, a substantially cubic-shaped element denotes the area normally occupied by a functional card reading mechanism (e.g., a star wheel).

We claim:

The ornamental design for a record card reader, as shown and described.
